[57] CLAIM

The ornamental design for a safety ladder with safety kit, as shown and described.

DESCRIPTION

FIG. 1 is a rear elevational view of the safety ladder with safety kit of the present invention;

FIG. 2 is a front elevational view of the safety ladder with safety kit of FIG. 1;

FIG. 3 is a right side elevational view of the safety ladder with safety kit of FIG. 1;

FIG. 4 is a left side elevational view of the safety ladder with safety kit of FIG. 1;

FIG. 5 is a top plan view of the safety ladder with safety kit of FIG. 1; and,

FIG. 6 is a bottom plan view of the safety ladder with safety kit of FIG. 1.

The stile on the ladder portion of the claimed design has been broken to indicate indefinite length of the ladder.
